(57) **CLAIM**

The ornamental design for a chemistry toy set as shown and described.

DESCRIPTION

FIG. 1 is a front perspective view of a chemistry toy set in accordance with a first embodiment of the present invention; FIG. 2 is a front view of the chemistry toy set of FIG. 1; FIG. 3 is a rear view of the chemistry toy set of FIG. 1; FIG. 4 is a right side view of the chemistry toy set of FIG. 1;

FIG. 5 is a left side view of the chemistry toy set of FIG. 1; FIG. 6 is a top view of the chemistry toy set of FIG. 1; FIG. 7 is a bottom view of the chemistry toy set of FIG. 1; FIG. 8 is a front perspective view of a chemistry toy set in accordance with a second embodiment of the present invention;

FIG. 9 is a front view of the chemistry toy set of FIG. 8; FIG. 10 is a rear view of the chemistry toy set of FIG. 8; FIG. 11 is a right side view of the chemistry toy set of FIG. 8;

FIG. 12 is a left side view of the chemistry toy set of FIG. 8;

FIG. 13 is a top view of the chemistry toy set of FIG. 8; FIG. 14 is a bottom view of the chemistry toy set of FIG. 8; FIG. 15 is a front perspective view of a chemistry toy set in accordance with a third embodiment of the present invention;

FIG. 16 is a front view of the chemistry toy set of FIG. 15; FIG. 17 is a rear view of the chemistry toy set of FIG. 15; FIG. 18 is a right side view of the chemistry toy set of FIG. 15;

FIG. 19 is a left side view of the chemistry toy set of FIG. 15;

FIG. 20 is a top view of the chemistry toy set of FIG. 15; and,

FIG. 21 is a bottom view of the chemistry toy set of FIG. 15. Any broken lines, which are shown throughout in the drawing figures, form no part of the claimed design.
